UNITED STATES PATENT OFFICE

DANIEL W. SMITH, OF OAK PARK, ILLINOIS, ASSIGNOR TO INTERNATIONAL HARVESTER COMPANY, A CORPORATION OF NEW JERSEY

TRIP ADJUSTER FOR GRAIN BINDERS

Application filed August 19, 1930. Serial No. 476,358.

This invention relates to binding mechanisms for grain binders and the like, and particularly to clutch tripping and compressor mechanisms therefor.

As is well known, these mechanisms comprise a plurality of rotatable shafts, to-wit, a knotter, a needle, and packer shafts, so timed in their operation by operative connections and a tension device, to be herein-after described, that they control the size of the bundles of grain formed and the discharge thereof. Due sometimes to careless assembly, sometimes to the difficulty in manufacturing tension devices of uniform strength, and sometimes after usage to the wearing of certain parts, these operative connections between the shafts mentioned develop a looseness or lost motion with a consequent undesirable rattling and chattering of the parts. The greatest disadvantage of this looseness, however, lies in the formation of bundles varying in size due to the irregular operation of the tripping and compressor mechanism.

The object of the invention is to improve the binding mechanism of a grain binder or the like machine, and especially the tripping and compressing device thereof, in such a manner that improved bundles of uniform size are formed. This is accomplished by the provision of an improved take-up or tension adjusting device, easily and quickly adjustable to compensate for any lost motion between the parts and thereby insure the proper tension on and operation of the tripping mechanism. Such adjustment is effected by novel means permitting change of tension without lengthening of the device, so that pivot centers always remain the same distance apart.

Another object is to improve generally the construction and operation of devices of this character.

The embodiment of the invention chosen for purposes of illustration is shown in the

accompanying sheet of drawings, wherein—

Figure 1 is a front end elevation of a binder mechanism equipped with the improved tension adjusting device;

Figure 2 is an elevational view of the tension adjuster per se;

Figure 3 is a view similar to Figure 2 but showing a different tension without having elongated the device between its pivot centers;

Figure 4 is a side view of the tension device;

Figure 5 is a cross sectional view along the line 5—5 appearing in Figure 2; and,

Figure 6 is a face detail view of the slide block.

The binder shown is of standard construction and comprises a binder frame 10 disposed adjacent the binder deck 11, the binding mechanism thereof (not shown) being controlled by a rotatable clutch dog 12 operable from the packer shaft 13, the dog in turn being governed in its operation by a stop link or member 14. This stop member is fixed on the shaft 15 which carries adjacent its farther end, a bracket 16 supporting the usual compressor trip 17, the latter extending upwardly into the path of the grain passing over the binder deck 11 in a well known manner. A crank 18 integral with one end of the needle shaft 19 is connected by means of a trip rod or link 20 with a rotatable cam wheel 21 keyed to the knotter shaft 22, and a cam wheel crank or lever 23 pivoted at 24 contacts at one end, by means of the cam roller 25, with a cam surface 26 formed integrally with the wheel 21.

The outer free end of the lever 23 is pivotally connected to a bolt or pin 27 carried in an elongated U-shaped strap 28 having near its upper end opposed, elongated slots 29, which slidably receive ears 30 which carry top and bottom plates 31, 32, respectively, integrally formed therewith to serve as a slide block. The plate 31 has a recess 33 in line

with a hole 34 in the bottom plate 32. A nut 35 is then fitted between the plates, as shown, and a threaded rod 36 is then passed upwardly through a hole in the bight of the U-strap 28, said threaded rod being slid through hole 34, through the nut 35, and finally seated with its upper end in the recess 33 in the top plate 31. A pin 37 then secures the nut 35 to the rod 36. A coil spring 38 is next provided to encircle the rod 36 within the housing 28 with an end of the spring abutting the bight of said U-strap housing 28. A square nut 39 is threadedly carried by the rod 36 and serves as a stop for the other end of the spring and, as the nut 39 is disposed between two flat parallel straps 28, it can only be turned on the rod by turning the housing 28 to carry the nut 39 with it. In this fashion the tension of the spring may be altered as will be clear. The lower end of the rod 36 carries a bent end 40 detachably and pivotally connected by a pin 41 to the free end of the trip arm 14. By so changing the spring tension, the proper size of bundles is controlled. The tension spring, by exerting a pull on the end of the lever 23, also serves constantly to urge the cam roller 25 to duty on the cam surface 26.

When the clutch dog 12 is abutting against the stop link 14, the compressor trip 17 is in position to receive and support an accumulation of grain moving to it from the binder deck 11. Gradually the pressure of the grain increases and, against the tension of the spring 38, moves the trip outwardly and downwardly. Because the stop member 14 is keyed to the same shaft which carries the trip, the stop is moved out of engagement with the dog 12. The packer shaft 13 now drives the cam wheel 21 through gearing 42 and 43 and, through the rod 20 and crank 18, imparts a part rotation or rocking movement to the needle shaft 19 to operate the needle carried thereby, not shown. This shaft is provided with a cam collar 44, which functions once on every such rotation to hold the stop member 14 in a raised position away from the clutch dog 12. At this time, of course, the cam roller 25 is traveling the low part of the cam 26 and the compressor trip 17 moves still farther downwardly and drops below the binder deck to permit discharge of the tied bundle.

If wear has resulted and the tension of spring 38 is insufficient, then obviously the hook 40 can quickly be uncoupled to permit of turning the rod 36 by hand to change the position of the nut 39 to place more tension on the spring. A comparison of Figures 2 and 3 shows that changing spring tension in this manner does not elongate the tension connector device and, as a result, the distance between its pivot centers is always maintained uniform.

It is to be understood that the invention is not to be limited to the specific form shown

herein, but may be modified to assume other forms without departing from its spirit, the intention being to include all such forms of the invention within the scope of the appended claims.

What is claimed is:

1. A tension device to be connected between the cam lever and compressor shaft trip of a binder, said device comprising a housing adapted to be pivotally connected to the cam lever, a block slideable in the housing, a rod turnably anchored in the slide block and having an end slidably passed through an end of the housing and adapted to be pivotally connected to the compressor shaft trip, a spring encircling the rod within the housing, and a nut positioned on a threaded part of the rod within the housing and serving as a stop for an end of the spring. 70

2. A tension device to be connected between the cam lever and compressor shaft trip of a binder, said device comprising a housing pivotally connected to the cam lever, said housing having opposite slots, a slide block having ears slideable in said slots, a rod turnably anchored in the slide block and having an end slidably passed through an end of the housing and pivotally connected to the compressor shaft trip, a spring encircling the rod within the housing, and a nut positioned on a threaded part of the rod within the housing and serving as a stop for an end of the spring. 80

3. A tension device to be connected between the cam lever and compressor shaft trip of a binder, said device comprising a housing, a block slideable in the housing, a rod turnably anchored in the slide block and having an end slidably passed through an end of the housing, a spring encircling the rod within the housing, and a nut positioned on a threaded part of the rod within the housing and serving as a stop for an end of the spring. 90

4. A tension device to be connected between the cam lever and compressor shaft trip of a binder, said device comprising a housing, said housing having opposite slots, a slide block having ears slideable in said slots, a rod turnably anchored in the slide block and having an end slidably passed through an end of the housing, a spring encircling the rod within the housing, and a nut positioned on a threaded part of the rod within the housing and serving as a stop for an end of the spring. 100

5. A tension device to be connected between the cam lever and compressor shaft trip of a binder, said device comprising a housing pivotally connected to the cam lever, said housing having opposite slots, a slide block having ears slideable in said slots, a rod anchored in the slide block and having an end slidably passed through an end of the housing and pivotally connected to the compressor shaft trip, a spring encircling the rod within the housing, and a stop for the spring positioned on the rod within the housing. 110

said stop being movable to vary the tension of the spring.

6. A tension device to be connected between the cam lever and compressor shaft trip of
5 a binder, said device comprising a housing, a block slideable in said housing, a rod turn-
ably anchored in the slide block and having an end slidably passed through an end of
10 the housing, a spring encircling the rod within the housing, and a stop for the spring positioned on the rod within the housing, said stop being movable along the rod to vary the tension of the spring.

In testimony whereof I affix my signature.
